LOUVER WIRE FEEDING DEVICE

Robert A. Christy, Park Forest, Ill., assignors to Borg-Warner Corporation, Chicago, Ill., a corporation of Illinois

Application December 22, 1951, Serial No. 262,992

5 Claims. (Cl. 271—2.3)

The present invention relates in its broadest aspects to web feeding devices and more particularly to an arrangement or device for controlling the supply of thin, flat, flexible metal wire maintained in a storage bin.

The principal object of the present invention is to provide means for controlling the supply of flat metal wire maintained in a storage bin from which the wire is intermittently withdrawn, so that the quantity of wire is sufficient to permit the intermittent withdrawal thereof from the bin without allowing the wire to accumulate in the bin so that it might be deformed beyond its elastic limit.

Another object of the present invention is to provide a feeding device for feeding wire into a storage bin, wherein the feeding device is capable of supplying the wire at a high feed rate when the quantity of wire within the bin is below a predetermined amount, and at a low feed rate when the quantity of wire within the bin is above a predetermined amount.

Another object of the invention is to provide a device for sensing the quantity of wire in the storage bin and when the quantity is above a predetermined amount to cause the wire to be fed into the bin at a low rate and when the quantity of wire in the bin is below a predetermined amount to cause the wire to be fed into the bin at a high rate.

Another object of the present invention is to provide a device for constantly feeding a continuous wire into a storage bin, wherein the feeding device is driven by a reciprocable motor having a variable diameter drive pulley. In this connection, the motor may be moved in one direction whereby the diameter of the drive pulley is decreased in order to effect a low feed rate for the wire, and may be moved in the opposite direction to increase the diameter of the drive pulley in order to increase the rate at which the wire is fed into the storage bin.

Another object of the invention is to provide fluid pressure responsive means for moving the driving motor into either its low feed rate or high feed rate position and to provide control means for the fluid pressure responsive means, which control means are responsive to the quantity of wire in the storage bin.

Another object of the invention is to provide, in the control means for moving the motor to either its high feed rate or low feed rate position, delaying devices which prevent movement of the motor from one of its positions to the other and a consequent change in the wire feed rate until a condition of under-supply or over-supply of wire in the storage bin prevails for a predetermined interval of time. In this connection a pair of control relays are provided with associated condensers for delaying a deenergization of the relays so as to cause a change in the wire feed rate which would normally take place in accordance with the quantity of wire in the storage bin as sensed by the wire sensing means.

Due to the fact that the wire is intermittently withdrawn from the storage bin and continuously fed thereto, it frequently happens that the wire bounces against the sensing means, very rapidly engaging and disengaging it. If the driving motor reciprocating means were actuated in response to each engagement and disengagement

2

between the wire and the sensing means, the motor would be in a continuous state of reciprocation. This undesirable state of conditions, however, is prevented by the delaying devices and each wire feed rate prevails for at least a predetermined interval of time.

The present invention finds particular utility in the weaving machine art, as exemplified by the U. S. patent to W. B. Ewing, 2,223,317, wherein long lengths of a thin flat louver wire are intermittently fed into the weaving machine. In weaving machines of this type it is essential that the louver wires be straight and have substantially no bends throughout their entire lengths, for in case the wires are bent, the friction between them and the operating parts of the machine, through which they must pass, is sufficient to stop the wires before they reach the proper position and in such case the weaving machine will not function properly. The present invention therefore solves a long existent problem in a simple and convenient manner by providing a storage bin for the louver wire and a control mechanism for the device for feeding the wire into the storage bin which maintains a sufficient quantity of wire in the bin at all times to satisfy the requirements of the weaving machine with which the present invention may be associated and which maintains a sufficiently small amount of louver wire in the storage bin so that the wire will not be permanently bent.

The above and numerous other objects and advantages of the present invention will become apparent from the following detailed description when read in conjunction with the accompanying drawings which illustrate a preferred embodiment of the invention, wherein:

Fig. 1 is a more or less schematic illustration showing the storage bin in plan view and the electrical and fluid pressure responsive control means for controlling the reciprocation of the driving motor;

Fig. 2 is a sectional view taken substantially along the line 2—2 in Fig. 1 and showing the driving motor and the associated weaving machine for utilizing the louver wire stored in the storage bin;

Fig. 3 is a fragmentary side elevational view, shown partly in section, and taken substantially along the line 3—3 in Fig. 2; and

Fig. 4 is a fragmentary perspective view of the louver wire feed rollers.

The preferred embodiment of the invention, as exemplified by the accompanying drawings, wherein like reference numerals in the different views identify identical parts, will now be described. The present invention utilizes a wire flattening and feeding mechanism 10, drive mechanism 11 for driving the flattening and feeding mechanism 10, a relatively shallow wire storage bin 12, a control mechanism 13 for controlling the speed of operation of the wire flattening and feeding mechanism 10, and finds particular utility when used in association with a weaving machine 14 of the general type disclosed in detail in the aforementioned patent to W. B. Ewing.

The wire flattening and feeding mechanism 10 includes a housing 15 rigidly mounted in a suitable manner on a frame 16 and suitably disposed within the housing 15 is a set of gearing (not shown in detail) for transmitting rotary motion from a pulley 17 to a pair of flattening and feeding rollers 18. The flattening and feeding rollers 18 are respectively driven in counterclockwise and clockwise directions, as indicated by the arrows in Fig. 1, in order to advance a round metallic wire 19 therebetween. The rollers 18 are sufficiently close together so as to not only engage and advance the wire, but also to compress the wire 19 to form a substantially flat elongated louver wire 20. The wire 19 may be drawn from a supply reel (not shown) having a large supply of the wire thereon and for the purposes of the present invention it can be considered that the wire 19 is substantially continuous.

Also, for the purposes of the present invention, it may be considered that the flat louver wire 20 is also substantially continuous.

The plane of the louver wire 20, upon emerging from between the rollers 18, is vertical and as it emerges it passes into the storage bin 12. As is most clearly shown in Fig. 2, the storage bin 12 comprises substantially flat top and bottom members identified by reference numerals 21 and 22, respectively, and the top member 21 of the storage bin 12 is substantially parallel to the bottom member 22, the members 21 and 22 being spaced apart by a distance only slightly greater than the width of the louver wire 20. Preferably, the bottom member 22 is made of metal to provide strength and is covered with glass to minimize the friction between it and the wire 20. The top member 21 is made of glass or some other transparent material. By making the top member 21 of the storage bin 12 of a transparent material the disposition of the louver wire 20 within the bin 12 may be readily seen. A contact plate 23 is disposed at one end of the bin and is electrically insulated from all parts of the bin 12 by means of an insulator strip 24. The storage bin 12 has a louver wire exit opening 25 in the corner of the bin diametrically opposite to an entrance opening 26 through which the louver wire 20 passes as it comes into the storage bin 12.

A block 27, mounted outside the bin 12 and adjacent the exit opening 25, has one corner rounded off, as indicated at 28, and acts as a guide for the louver wire 20 after it leaves the storage bin 12 and until it reaches a pair of weaving machine feed rolls 29 and 30. It will be noted that the rounded corner 28 of the block 27 is substantially tangent to the line of travel of the louver wire 20 as it leaves the storage bin 12 and is also substantially tangent to the line of travel of the louver wire 20 in passing from contact with the block 27 into the feed rolls 29 and 30. The radius of curvature of the rounded off corner 28 of the block 27 is sufficiently great so that the louver wire 20 is not bent beyond the limit of its elasticity. It is contemplated that the feed rolls 29 and 30 will operate so as to intermittently withdraw louver wire 20 from the storage bin 12 in order to advance the louver wire 20 into the weaving machine 14. It is further contemplated that the feed rollers 18 will function to continuously feed the louver wire 20 into the storage bin 12.

It has been found through experience that a prime source of trouble encountered in the weaving of screens employing flat louver wires results from the fact that the louver wire is bent slightly, and when this occurs friction, due to contact between the louver wire and the flat sides of the slot in the weaving machine through which the rolls 29 and 30 advance the louver wire, is so great as to prevent the complete advance of the louver wire through the entire length of the slot. In such cases the weaving machines jam and break down, with a considerable loss of operating time before they can again be placed in operating condition. It has thus been found that if the louver wire can be maintained straight while being advanced into the weaving machine by the feed rolls 29 and 30 a great number of break-downs of the weaving machines are avoided. The rounded corner 28 of the guide block 27 eliminates any bending of the louver wire 20 as it passes from the storage bin to the feed rolls 29 and 30 and the disposition of the entrance and exit slots 26 and 25 in the storage bin 12 also aid in preventing the formation of permanent bends in the louver wire 20.

Besides the contact plate 23, a number of louver wire directing blocks, each of which is made of a non-conducting plastic, are disposed within the storage bin 12 for directing the louver wire 20 in such a manner as to prevent the formation of permanent bends or kinks therein. The first one of these blocks comprises a generally rectangular plastic block 31 having one side 32 disposed in substantially parallel relation with the one side of the storage bin 12. The space between the side 32 of the block 31 and the side of the storage bin 12 is rather nar-

row but quite sufficient to permit the passage of the louver wire 20 therebetween. The block 31 has a rounded corner 33 for preventing the formation of permanent bends in the louver wire 20 if the louver wire should happen to be pulled around this corner 33. As will be noted, the guide-way formed by the side 32 of the block 31 and the side of the bin 12 serves to direct the louver wire 20 along one side of the bin toward the contact plate 23. Disposed in substantially parallel relation to the opposite side of the storage bin 12 is an elongated plastic guide block 34, with sufficient space being provided between the block 34 and the side of the bin 12 to permit the passage of the louver wire 20 therebetween as it leaves the storage bin 12 through the exit slot 25. The end of the guide block 34 opposite the exit slot 25 is rounded off as indicated at 35, to prevent the formation of permanent bends in the louver wire 20 as it is drawn around the end 35 of the guide block 34 when the feed rolls 29 and 30 feed the louver wire 20 into the weaving machine 14. In the space in the storage bin between the blocks 31 and 34 are disposed a pair of plastic guide blocks 36 and 37. The block 36 abuts the block 31 and the block 37 abuts the guide block 34. Sufficient space is provided between each of the blocks 36 and 37 to permit the passage of the louver wire 20 and the ends of the blocks 36 and 37 providing the passage for the louver wire 20 are both rounded off to prevent the formation of permanent bends in the louver wire 20. The space in the storage bin 12 defined by the blocks 31, 36, 37 and 35 permits a certain freedom of movement of the louver wire 20 and it has been found that this space is important in preventing the formation of bends in the louver wire 20.

As has been stated heretofore, the feed rolls 29 and 30 serve to intermittently advance the louver wire 20 into the weaving machine 14 and accordingly, the louver wire 20 disposed between the guide block 34 and the one side of the storage bin 12 is alternately stationary and moving. It has also been stated heretofore that the feeding and flattening rollers 18 function continuously to advance the louver wire 20 into the storage bin 12. As will be obvious, whenever the louver wire 20 is not being withdrawn from the storage bin 12 the feed rollers 18, in advancing the louver wire 20 into the bin 12, tend to cause a loop 38 to be formed in the wire 20. As is also apparent, the loop 38 continuously increases in size as long as the feed rolls 29 and 30 are stationary and due to the fact that the feed rolls 29 and 30 are capable of withdrawing the louver wire 20 at a much greater rate than the feed rolls 18 are capable of feeding the louver wire 20 into the storage bin 12, the loop 38 decreases very rapidly in size. When the loop 38 is of a size which permits it to touch the contact plate 23 or get very close to the contact plate 23 before the feed rollers 29 and 30 start to withdraw the louver wire 20 the optimum operating conditions prevail as there is then an adequate supply of louver wire in the loop 38 to satisfy the requirements of the rollers 29 and 30 and the weaving machine 14 without causing the loop 38 to be drawn down to such a small loop that it will be drawn tightly around the corners of the blocks 31, 36 and 34. It will also be seen that if the louver wire 20 is fed into the storage bin 12 at too great a rate then there will be too much wire in the storage bin 12 to be used by the weaving machine 14 and a large number of loops will form in the storage bin. As the loops which form in the bin 12 increase in number, the louver wire 20 is compressed and permanent bends are formed therein. Since a single loop 38 of louver wire 20, of a sufficient size to approximately fill the storage bin 12, that is, engage the contact plate 23, is sufficient to satisfy the requirements of the weaving machine for each operation of the feed rolls 29 and 30, it is desirable to operate the feed rolls 18 at a speed which is sufficient to form a loop of this size between successive operations of the feed rolls 29 and 30. Accordingly, it

would be desirable to have the feed rolls 18 operate at a constant rate of speed, which rate of speed is the exact rate required to form a single loop 38 in the storage bin 12 which substantially engages the contact plate 23. Due to a number of reasons, among which is the fact that it is impractical to attempt to have the feed rolls 18 driven at such an invariable rate of speed, the present invention contemplates the provision of means for driving the feed rolls 18 at a high rate of speed and a low rate of speed. When the rolls 18 are driven at their high rate of speed, they are capable of supplying a slightly greater quantity of louver wire 20 than is needed by the weaving machine 14. When the feed rolls 18 are driven at their low rate of speed they are capable of supplying a quantity of louver wire 20 which is slightly less than the requirements of the weaving machine 14. The present invention therefore provides means for causing the feed rolls 18 to be driven at their high rate of speed when the loop 38 of louver wire 20 is too small to engage the contact plate 23 and to drive the feed rolls 18 at their low rate of speed for so long as they are supplying a loop 38 of louver wire 20 which engages the contact plate 23.

The means for causing the feed rolls 18 to be driven at their high or their low rate of speed will now be described. The drive mechanism for driving the rolls 18 comprises an electric motor 38 having a variable diameter pulley 39 suitably affixed to its shaft, and a belt 40 is provided for transmitting the drive from the pulley 39 to the pulley 17 which is connected through suitable gearing (not shown) for driving the rolls 18. The variable diameter pulley 39 comprises two sections 41 and 42, both of the sections being rotatably fixed to the motor shaft 43 and the section 41 being longitudinally fixed to the motor shaft while the section 42 is longitudinally slideable on the shaft. Suitably fixed to the end of the motor shaft 43 is a cylindrical cap 44, and a compression spring 45 disposed around the motor shaft 43 abuts the cap 44 and is continuously effective to urge the pulley section 42 toward the pulley section 41. It will be noted that the pulley sections 41 and 42 are respectively provided with conical surfaces 41a and 42a which are engaged by the belt 40. As the sections 42 and 41 are moved closer together or farther apart the effective diameter of the pulley 39 is changed.

It can be assumed that the belt 40 is non-elastic and that the strength of the compression spring 45 is sufficient to maintain the belt 40 under sufficient tension to at all times maintain the necessary frictional contact between the belt 40 and the conical surfaces 41a and 42a to enable the motor to drive the pulley 17. Therefore, in order to change the effective diameter of the pulley 39 it is only necessary to move the motor 38 toward or away from the pulley 17 within the limits afforded by the radial dimensions of the pulley sections 41 and 42. Thus, when the motor 38 is moved downwardly, as viewed in Figs. 2 or 3, the compression spring 45 is further compressed and the effective diameter of the pulley 39 is decreased so that the driving ratio between the motor shaft 43 and the rolls 18 will be a low speed ratio. If the motor 38 is moved upwardly relative to the pulley 17 the compression spring 45 expands, the belt 40 engaging the conical surfaces 41a and 42a along lines defined by greater radii from the center of rotation of the motor shaft 43 and the effective diameter of the pulley 39 is increased so that there will be a high speed driving ratio between the motor shaft 43 and the rolls 18.

The mechanism for reciprocating the motor 38 toward and away from the pulley 17 so as to vary the effective diameter of the variable diameter pulley 39 and thereby change the driving ratio between the pulley 39 and the feed rolls 18 will now be described. The motor 38 is suitably secured, as by bolts 46, to a base plate 47. A frame member 48 is suitably secured to the main frame 16 and a guide block 49 is rigidly bolted to the

frame member 48. The guide block 49 is provided with a pair of dovetail grooves 50 for receiving corresponding dovetail projections 51 on the base plate 47. The dovetail projections 51 are slideable in the dovetail grooves 50 in order to permit reciprocation of the motor 38 toward and away from the pulley 17. A lug 52, integrally secured to the guide block 49 is formed with a projection 53 having an aperture 54 extending therethrough. A long threaded adjusting bolt 55 is threaded through the base plate 47 and has a non-threaded portion 56 which passes through the aperture 54 in the projection 53. On the end of the non-threaded portion 56 of the adjusting bolt 55 is a knob 57 which is suitably secured to a link 58 pivotally connected to a bell crank 59. The bell crank 59 is pivoted, as indicated at 60, to a projection 61 secured to the frame member 48. The other end of the bell crank 59 is suitably pivoted to a piston rod 62 of a fluid pressure responsive motor 63.

The fluid pressure responsive motor 63 comprises a cylinder 64 suitably secured to the frame member 48 and reciprocable within the cylinder 64 is a piston 65 integral with or secured to the piston rod 62. Fluid transmitting conduits 66 and 67 are connected to the cylinder 64 at opposite ends thereof for transmitting fluid under pressure into or bleeding fluid from the cylinder 64 so as to move the piston 65 to either end of the cylinder.

It is contemplated that any suitable fluid, such as air or oil, by way of example only, when under pressure 30 may be utilized for reciprocating the piston 65 to the left or to the right as viewed in either Fig. 1 or 2. When fluid under pressure is admitted into the cylinder 64 through the conduit 66, the piston 65 is moved to the right, thereby pivoting the bell crank 59 in a counter-clockwise direction about its pivot point 60 and lifting the bolt 55 and motor 38. When the motor is lifted in this manner, the compression spring 45 functions to compress the pulley section 42 toward the pulley section 41 thereby increasing the effective diameter of the variable diameter pulley 39 and, in turn, increasing the driving ratio between the pulley 39 and the louver wire feed rolls 18. When fluid under pressure is admitted into the cylinder 64 through the conduit 67, the piston 65 is moved to the left, thereby causing the bell crank 59 to pivot in a clockwise direction about its pivot point 60 and, in turn, causing the motor 38 to be lowered. This causes the compression spring 45 to be further compressed and the sections 41 and 42 to be spread apart relative to each other so as to decrease the effective diameter of the variable diameter driving pulley 39. The driving ratio between the pulley 39 and the feed rolls 18 is correspondingly decreased under these conditions.

Any suitable valve may be utilized for controlling the supply of fluid pressure to the cylinder 64 through the conduits 66 and 67 and accordingly no specific disclosure of the valve has been made herein. A schematic showing of a valve which may be utilized for controlling the fluid pressure supplied to the cylinder 64 is indicated generally by reference numeral 68 and comprises a valve housing 69 having a pressure inlet conduit 70, a bleed conduit 71 and suitable ports communicating respectively with the conduits 66 and 67. The valve itself is represented by reference numeral 72 and is normally biased to the right by a tension spring 73, suitably secured at its other end to a stationary member, and the valve may be moved to the left by energizing a valve solenoid 74 by the passage of electric current therethrough. When the solenoid 74 is energized, the valve 72 is moved to the left against the bias of the spring 73 and this causes communication to be established between the fluid pressure inlet conduit 70 and the conduit 66, thereby causing fluid pressure to be applied to the left face of the piston 65 so as to cause the piston 65 to be moved to the right, thereby lifting the

motor 38 and establishing the high speed driving ratio between the pulley 39 and the driving feed rolls 18, so as to advance the louver wire 20 into the storage bin 12 at its high feed rate. Under this condition, communication is established between the conduit 67 and the bleed conduit 71 so that the fluid on the right side of the piston 65 in the cylinder 64 is bled out through the conduits 67 and 71. When the solenoid 74 is de-energized, the tension spring 73 is effective to move the valve 72 to the right, thereby establishing fluid pressure communication between the conduit 70 and the conduit 67. Simultaneously, communication is established between the conduit 66 and the conduit 71. At this time fluid is bled from the left end of the cylinder 64 through the conduits 66 and 71 and fluid under pressure is applied to the right end of the cylinder 64 through the pressure inlet conduit 70 and the conduit 67 so as to move the piston 65 to the left, thereby lowering the motor and decreasing the effective diameter of the variable diameter pulley 39. This causes the low speed driving ratio to be established between the variable diameter pulley 39 and the feed rolls 18 so that the louver wire 20 is fed into the storage bin 12 at its low feed rate.

The means for controlling the operation of the valve 68 so as to in turn control the rate at which the louver wire 20 is fed into the storage bin 12, will now be described. A pair of electric power transmitting lines 75 and 76 provide a suitable source of alternating current for energizing the primary winding 77 of a combined transformer and rectifier, indicated schematically by reference numeral 78. The combined transformer and rectifier 78 also includes three secondary windings 79, 80 and 81, as well as rectifying tube 82, the cathode 83 of which is connected to the ends of the secondary winding 81 and the plates 83a of which are respectively connected with the ends of the secondary winding 79. The rectifying tube 82 and the secondary windings 79 and 81 function in a well-known manner to provide a suitable source of direct current for a pair of leads 84 and 85.

The control circuit for controlling the operation of the valve 68 also includes a sensing relay 86 which is energized and deenergized respectively in accordance with the quantity of louver wire 20 in the storage bin 12. The control circuit also includes a low speed relay 87, a high speed relay 88, a high speed indicator light 89 and a low speed indicator light 90.

The sensing relay 86 comprises a winding 91, and a stationary contact 92, together with a movable contact 93, comprise a sensing switch which is closed whenever the winding 91 of the sensing relay 86 is energized. The housing 15 for the gearing for driving the feed rolls 18 is grounded as indicated at 94 and when the loop 38 of the louver wire 20 engages the contact plate 23 an electrical circuit for energizing the winding 91 of the sensing relay 86 is completed and this circuit extends from the ground 94, through the flattening and feeding mechanism 10, through the louver wire loop 38, through the contact plate 23, through a lead 95, through the winding 91 of the relay 86, through a lead 96, through the secondary winding 80 which provides a source of alternating current and through a lead 97 to ground 98. Thus, it is apparent that the sensing switch comprising the contacts 92 and 93 is closed whenever the louver wire loop 38 engages the contact plate 23 and open whenever the louver wire loop 38 is disengaged from the contact plate 23.

The low speed relay 87 comprises a winding 99, the ends of which are respectively connected with leads 100 and 101. A condenser 102 bridges the leads 100 and 101 and a pair of contacts 103 and 104 are also included in the relay 87. Whenever the winding 99 of the low speed relay 87 is deenergized the movable contact 103 engages the stationary contact 104 and upon 75

energization of the winding 99, the contact 103 is pulled up so as to break the connection between the contact 103 and the contact 104. Whenever the sensing switch comprising the contacts 92 and 93 is closed, an energizing circuit is established for the low speed relay 99 and this circuit extends from the lead 84, through the lead 101, through the winding 99 of the low speed relay 87, through the lead 100, through the sensing switch comprising the contacts 92 and 93, through a lead 105 to the lead 85. Also, when the energizing circuit for the winding 99 is completed, a circuit is also established for charging the condenser 102. The condenser 102 functions, upon the opening of the sensing switch comprising contacts 92 and 93, to maintain the winding 99 of the low speed relay 87 energized for a predetermined time interval thereafter so that the contacts 103 and 104 are not immediately closed upon an opening of the sensing switch.

The high speed relay 88 comprises a winding 106 having its ends respectively connected with a lead 107 and with a lead 108. The lead 107 is connected with the lead 84 and the lead 108 is connected with the stationary contact 104 of the relay 87. When the relay 99 is de-energized its movable contact 103 engages its stationary contact 104 and an energizing circuit is established for the winding 106 of the high speed relay 88, which circuit extends from the lead 84, through the lead 107, through the winding 106 of the relay 88, through the lead 108, through the closed contacts 104 and 103 of the relay 87 and through a lead 109 to the lead 85. The high speed relay 88 also includes a condenser 110 for delaying the deenergization of the winding 106 after the contact 103 is opened from its associated contact 104. As is obvious, the condenser 110 bridges the lead 107 and 108 and is connected in parallel with the winding 106. The high speed relay 88 also includes a pair of stationary contacts 111 and 112 and a movable contact 113. When the winding 106 is energized the movable contact 113 is pulled up to engage the stationary contact 111 to thereby complete an energizing circuit for the valve solenoid 74, which circuit extends from the line 76, over a lead 114, through the closed contacts 113 and 111, through a lead 115, through the winding of the solenoid 74, and through a lead 116 to the line 75. An energizing circuit is also established whenever the solenoid 74 is energized, for illuminating the high speed indicator light 89 and this circuit extends from the lead 115 through the high speed indicator light 89 and through a lead 117 to the lead 116.

When the high speed relay 106 is deenergized its movable contact 113 falls back into engagement with the stationary contact 112 and a circuit is established for illuminating the low speed indicator light 90. This circuit extends from the line 76, through the lead 114, through the closed contacts 113 and 112, through a lead 118, through the low speed indicator light 90, through the lead 117 and through the lead 116 to the line 75.

The operation of the control circuit and the mechanism for correlating the rate at which the louver wire 20 is fed into the storage bin 12 in accordance with the amount of louver wire in the bin will now be described. When the louver wire loop 38 is too small to engage the contact plate 23, the sensing relay 86 is deenergized and the sensing switch comprising contacts 92 and 93 is open. At this time the winding 99 of the low speed relay 87 is deenergized and its movable contact 103 is engaged with the stationary contact 104. When the contacts 103 and 104 are closed, an energizing circuit is established for the high speed relay 106, thereby causing the movable contacts 113 to be engaged with the stationary contact 111. This completes an energizing circuit for the valve solenoid 74 and for the high speed indicator light 89. When the valve solenoid 74 is energized the valve 72 is moved to the left to connect the conduit 70 with the conduit 66 and the conduit 67 with

the conduit 71. Fluid under pressure is thereby admitted into the left end of the cylinder 64 behind the piston 65 and fluid is bled from the right end of the piston 64. The piston 65 thereby moves to the right and causes the motor 38 to be moved to its upper position so as to allow the effective diameter of the variable diameter driving pulley 39 to be enlarged. This causes the flattening and feeding rolls 18 to be driven at their high feed rate so as to feed the louver wire 20 into the storage bin 12 at a high rate of speed.

As long as the louver wire 20 continues to be fed into the storage bin 12 at the high feed rate the supply of louver wire 20 in the storage bin 12 between each intermittent withdrawal thereof by the feed rolls 29 and 30 increases. Under these conditions the input rate exceeds the overall withdrawal rate of the louver wire by the feed rolls 29 and 30. Consequently, the size of the louver loop 38 immediately preceding the withdrawal of the louver wire 20 by the intermittent operation of the feed rolls 29 and 30, eventually increases until the loop 38 engages the contact plate 23. Upon the engagement of the loop 38 with the contact plate 23, the winding 91 of the sensing relay 86 is energized and the sensing switch comprising the contacts 92 and 93 is closed. The closure of the sensing switch completes an energizing circuit for the low speed relay winding 99 and a circuit for charging the condenser 102. During the condition when the feed rolls 29 and 30 begin to withdraw the louver wire 20 from the storage bin 12 almost immediately after the loop 38 engages the contact plate 23, the energizing circuit for the sensing relay 91 is completed only momentarily and the sensing switch comprising the contacts 92 and 93 is closed only momentarily. Momentary closure of the sensing switch is insufficient to enable the condenser 102 to become charged, and, accordingly, as soon as the sensing switch opens, or at least very soon thereafter, the winding 99 of the low speed relay 87 becomes de-energized and its movable contact is disengaged from its stationary contact 104 for a very short interval of time. Because of the fact that the contact 103 reengages the contact 104 before the condenser 110 has been completely discharged, the winding 106 of the high speed relay 88 is not actually deenergized and the movable contact 113 is maintained in its up position in engagement with the contact 111 so as to continue to maintain the valve solenoid 74 in its energized condition. This, in turn, causes the louver wire 20 to continue to be fed at the high feed rate.

When the high feed rate of the louver wire prevails for a considerable period of time, the loop 38 contacts the contact plate 23 for a relatively long interval before the louver wire is withdrawn by the feed rolls 29 and 30. Under these conditions, the sensing relay 91 remains energized and the sensing switch comprising the contacts 92 and 93 remains closed for a sufficient duration to fully charge the condenser 102 and fully energize the winding 99 of the low speed relay 87. At this time, the contact 103 is pulled up to break its electrical connection with the contact 104 and the energizing circuit for the winding 106 of the high speed relay 88 is broken. The condenser 110 which bridges the leads 107 and 108 discharges, maintaining the winding 106 energized for a short period of time, however, if the contact 103 is held disengaged from the contact 104 for a sufficient interval, the condenser 110 completely discharges and the movable contact 113 falls into engagement with the stationary contact 112. The breaking of the electrical connection between the movable contact 113 and the stationary contact 111 causes deenergization of the valve solenoid 74 and the spring 73 is effective to move the valve 72 to the right, in which position the fluid pressure input conduit 70 is connected with the conduit 67 and the fluid pressure bleed conduit 71 is connected with the conduit 66. At this time, fluid under pressure is admitted into the cylinder 64

on the right side of the piston 65 and causes the piston to move to the left, thereby lowering the motor 38 and decreasing the effective diameter of the driving pulley 39. This causes a change in the driving ratio between the pulley 39 and the feed rolls 18 so that the louver wire 20 is thereafter fed into the storage bin 12 at its low feed rate.

The louver wire 20 is fed into the storage bin 12 at the low feed rate until the duration of the periods of contact between the loop 38 and the contact plate 23 is sufficiently short to enable the condenser 102 to completely discharge between successive closures of the sensing switch comprising the contacts 92 and 93. As the periods of deenergization of the low speed relay winding 99 become successively longer due to the fact that the louver wire loop 38 engages the contact plate 23 for shorter and shorter intervals of time between successive withdrawals of the louver wire by the feed rolls 29 and 30, the energizing circuit for the winding 106 of the high speed relay 88 is completed for longer intervals. When the intervals, while the winding 106 is energized, become sufficiently long to fully charge the condenser 110, the relay winding 106 is able to exert sufficient magnetic attraction to pull up the contacts 113 and thereby again complete the energizing circuit for the valve solenoid 74. At such time as the valve solenoid 74 is again energized, the fluid pressure circuit for raising the motor is established and the high feed rate for the louver wire is again established.

30. Due to the fact that considerable force is required to raise the motor 38, it is undesirable that it be raised in order to change the feed rate of the louver wire to the high feed rate, or to be lowered in order to change the feed rate to the low feed rate with each opening and closure of the sensing switch comprising contacts 92 and 93. The condensers 102 and 110 respectively associated with the low speed relay 87 and the high speed relay 88 provide a certain amount of delay, which may be of the order of two to three seconds, for preventing a change in the feed rate of the louver wire 20 until such time as the quantity of louver wire in the storage bin 12 definitely exceeds or is less than that predetermined quantity which is necessary in order to have the loop 38 just engage the contact plate 23 prior to withdrawal of the louver wire from the storage bin 12 by the feed rolls 29 and 30. By utilizing the condensers 102 and 110 in the manner in which they are used herein, continuous reversals of movements of the valve 72 and consequent raising and lowering of the motor 38 to effect changes in the effective diameter of the variable diameter pulley 39, take place only when such a change in the feed rate for the louver wire is definitely called for.

It will accordingly be apparent to those skilled in the art that the present invention provides a simple and efficient device for controlling the supply of wire maintained in a storage bin from which the wire is intermittently withdrawn. It is contemplated that numerous changes and modifications may be made in the invention without departing from the spirit and scope thereof.

What is claimed is:

1. In a device for controlling the supply of wire maintained in a storage bin, feeding means for feeding the wire into the bin either at a high rate or a low rate, means for intermittently withdrawing said wire from the bin and an electrical circuit including a wire sensing switch adapted to close when the quantity of wire in the bin exceeds a predetermined amount and adapted to open when the quantity of wire in the bin is less than said predetermined amount, said withdrawing means upon each intermittent operation thereof being effective to withdraw the wire from the bin at a substantially greater rate than either rate at which said feeding means feeds the wire into the bin whereby said wire alternately effects opening and closure of said sensing switch.

upon each intermittent withdrawal of wire from said bin, said electrical circuit being effective to control said feeding means so as to effect the high wire feed rate in response to an opening of said sensing switch and the low wire feed rate in response to a closure of said sensing switch, said electrical circuit including means for delaying changes in the rate the wire is fed into the bin by said feeding means for a predetermined interval of time after said wire sensing switch changes its condition from closed to open or vice versa.

2. In a device for controlling the supply of wire maintained in a storage bin, feeding means for feeding the wire into the bin either at a high rate or a low rate, means operable for intermittently withdrawing said wire from said bin at a rate substantially in excess of either said high or low feed rate and an electrical circuit including a wire sensing switch adapted to close when the quantity of wire in the bin exceeds a predetermined amount and adapted to open when the quantity of wire in the bin is less than said predetermined amount, the quantity of wire in the bin successively exceeding and being less than said predetermined amount upon each intermittent withdrawal thereof from said bin such that said sensing switch is alternately closed and opened, said electrical circuit including a pair of relays operable respectively upon the closure and opening of said wire sensing switch to control said feeding means so as to effect the low wire feed rate and the high wire feed rate, said electrical circuit also including a pair of condensers respectively associated with said relays for delaying the operation thereof for predetermined time intervals after the conditions of said wire sensing switch changes from closed to open or vice versa, whereby the wire is fed into the bin at said low rate for so long as the quantity of wire in the bin exceeds said predetermined amount for intervals, between said successive withdrawals, exceeding predetermined periods of time and at said high rate when the quantity of wire in the bin exceeds said predetermined amount for intervals, between successive withdrawals, of less than said predetermined periods of time.

3. In a device for controlling the supply of an electrical conductor maintained in a storage bin, means for feeding the conductor into the bin either at a high rate or a low rate, means for intermittently withdrawing the conductor from the bin, the feeding means being electrically grounded and the bin having an insulated electrical conducting plate disposed therein, a relay connected in series with said plate, the conductor when fed into the bin forming a loop which becomes larger as the quantity of the conductor in the bin increases and the conductor engaging said plate to complete an energizing circuit for said relay when said loop increases to a size corresponding to a predetermined quantity of the conductor in the bin, said withdrawing means, during each intermittent operation thereof, being effective to withdraw the wire from the bin at a substantially greater rate than the rate at which the feeding means feeds the wire into the bin whereby said loop of wire alternately is engaged with and disengaged from said plate, means rendered effective only after said relay remains energized for a predetermined time interval as a result of said conductor being in engagement with said plate for said interval for changing the rate at which the conductor is fed into the bin from said high rate to said low rate, and other means rendered effective only after said relay remains deenergized for a predetermined time interval as a result of said conductor being disengaged from said plate for said last-named interval for changing the rate at which the conductor is fed into the bin from said low rate to said high rate.

4. In a device for controlling the supply of an electrical conductor maintained in a storage bin, means for feeding the conductor into the bin either at a high rate or at a low rate, means for intermittently withdrawing the wire from said bin at a rate substantially in excess of either said high or said low feed rate, the feeding means being

electrically grounded and the bin having an insulated electrical conducting plate disposed therein, a relay connected in series with said plate, the conductor when fed into the bin forming a loop which becomes larger as the quantity of the conductor in the bin increases and the conductor engaging said plate to complete an energizing circuit for said relay when said loop increases to a size corresponding to a predetermined quantity of the conductor in the bin, said loop successively engaging and disengaging said plate upon each intermittent withdrawal of the conductor from said bin, a pair of contacts controlled by said relay adapted to close upon energization and open upon deenergization of said relay, a second relay connected in series with said pair of contacts and energized when said pair of contacts is closed, a condenser connected in series with said pair of contacts and in parallel with said second relay and adapted to discharge and maintain said second relay energized for a predetermined time interval after the opening of said pair of contacts, a second pair of contacts controlled by said second relay and adapted to close upon deenergization and open upon energization of said second relay, and means connected in series with said second pair of contacts and effective in accordance with the open or closed condition thereof for respectively causing said feeding means to feed the conductor into the bin at either said low rate or said high rate.

5. In a device for controlling the supply of an electrical conductor maintained in a storage bin, means for feeding the conductor into the bin either at a high rate or a low rate, means for intermittently withdrawing the wire from said bin at a rate substantially in excess of either said high or said low feed rate, the feeding means being electrically grounded and the bin having an insulated electrical conducting plate disposed therein, a relay connected in series with said plate, the conductor when fed into the bin forming a loop which becomes larger as the quantity of the conductor in the bin increases and the conductor engaging said plate to complete an energizing circuit for said relay when said loop increases to a size corresponding to a predetermined quantity of the conductor in the bin, said loop successively engaging and disengaging said plate upon each intermittent withdrawal of the conductor from said bin, a pair of contacts controlled by said relay and adapted to close upon energization and open upon deenergization of said relay, a second relay connected in series with said pair of contacts and energized when said pair of contacts is closed, a condenser connected in series with said second relay and adapted to discharge and maintain said second relay energized for a predetermined time interval after the opening of said pair of contacts, a second pair of contacts controlled by said second relay and adapted to close upon deenergization and open upon energization of said second relay, a third relay connected in series with said second pair of contacts and energized when said second pair of contacts is closed, a condenser also connected in series with said second pair of contacts and adapted to discharge and maintain said third relay energized for a predetermined time interval after the opening of said second pair of contacts, and means effective upon the energization or deenergization of said third relay for causing said feeding means to feed the conductor at said high rate or said low rate.
